(57) **CLAIM**

The ornamental design for an electronic device holder, as
shown and described.

DESCRIPTION

FIG. 1 is a perspective view of an electronic device holder
showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is second perspective view showing the electronic
device holder.

FIG. 9 is a partial cross-sectional view thereof along line 9-9
shown in FIG. 2; and,

FIG. 10 is a perspective view showing the electronic device
in use.

The broken lines in the drawings depict environmental
subject matter only and form no part of the claimed design.
